(57) **CLAIM**

The ornamental design for automobile light assembly, as shown and described.

DESCRIPTION

FIG. 1 is a perspective view of the automobile light assembly.

FIG. 2 shows the front of the automobile light assembly.

FIG. 3 shows the first side of the automobile light assembly.

FIG. 4 shows the second side of the automobile light assembly.

FIG. 5 shows the top of the automobile light assembly.

FIG. 6 shows the bottom of the automobile light assembly.

FIG. 7 shows a first exploded view of the automobile light assembly.

FIG. 8 shows a second exploded view of the automobile light assembly; and,

FIG. 9 shows a detail view of part of automobile light assembly.

The broken line showing of the rear structure is included for the purpose of illustrating the rear structure and forms no part of the claimed design.
